DESIGN.

—o—
N. KOMORI.

CARPET.

No. 17,731.

Patented Sept. 20, 1887.

UNITED STATES PATENT OFFICE.

NORIC KOMORI, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,731, dated September 20, 1887.

Application filed August 16, 1887. Serial No. 247,120. Term of patent 3½ years.

To all whom it may concern:

Be it known that I, NORIC KOMORI, of New York city, in the county and State of New York, have invented a new and original Design 5 for Carpets, of which the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

My design comprises a body part, A, and a border, B.

The body part A is made up of a number of sprays or stems of an irregular curving or twisting form, bearing flowers and leaves, all 20 disposed at intervals over the face of the carpet upon a ground ornamented with light skeleton leaf and stem work. The separate sprays of the pattern in most cases have one large prominent circular flower and one or 25 more buds or partly-opened blossoms. One spray supports a large bulb-like flower form. Another has a flower form with its outer leaves extended, but the inner ones closed around the

center of the flower. There are some smaller sprays with one or two small flowers or buds. 30 The skeleton leaves are somewhat shadowy in character and occupy the intervening spaces between the sprays.

My border B has an inner ornamental margin. Over its middle portion are scattered 35 separate sprays of the character already described, and between these sprays is a light and shadowy leaf and stem work underlying and extending between them. The outer margin of the border has at its lower edge a wav- 40 ing line of stems and narrow leaves, from which short stems project upward, supporting round fruit-like forms.

What I claim as new, and desire to secure by Letters Patent, is— 45

1. In a design for carpets, the body A, substantially as shown.
2. In a design for carpets, the border B, substantially as shown.
3. The design for carpets, consisting of the 50 body A and border B, substantially as shown.

NORIC KOMORI.
